The ornamental design for a vehicle roof top water tank, as shown and described.

DESCRIPTION

FIG. 1 is a top, back, left-side perspective view of a vehicle roof top water tank showing my new design;

FIG. 2 is a bottom, front, right-side perspective view thereof; FIG. 3 is a front view thereof, shown enlarged for ease of illustration;

FIG. 4 is a back view thereof, shown enlarged for ease of illustration;

FIG. 5 is a left-side view thereof;

FIG. 6 is a right-side view thereof;

FIG. 7 is a top view thereof; and,

FIG. 8 is a bottom view thereof.

The broken lines in the drawings show portions of the vehicle roof top water tank, which form no part of the claimed design.
